UNITED STATES PATENT OFFICE

150,033

DESIGN FOR A BRASSIÈRE

Jessie Schaefer, Buffalo, N. Y., and Hyman G. Imôn, Detroit, Mich., assignors to Jaye Imôn Inc., a corporation of New York

Application May 28, 1947, Serial No. 139,348

Term of patent 14 years

(Cl. D20—4)

To all whom it may concern:

Be it known that we, Jessie Schaefer and Hyman G. Imôn, both citizens of the United States, residing, respectively, at Buffalo, in the county of Erie and State of New York and at Detroit, in the county of Wayne and State of Michigan, have invented a new, original, and ornamental Design for Brassières, of which the following is a specification, reference being had to the accompanying drawing, forming part thereof.

Fig. 1 is a front elevational view of the Brassière showing our new design.

Fig. 2 is a front perspective view thereof as it appears with the lacing brought around and tied in the front.

Fig. 3 is a rear perspective view thereof, the lacing being shown broken away for purposes of illustration.

Fig. 4 is a side elevational view thereof.

We claim:

The ornamental design for a brassière, as shown.

JESSIE SCHAEFER.

HYMAN G. IMÔN.
